UNITED STATES PATENT OFFICE.

JAMES S. MILNE, OF BROOKLYN, NEW YORK, AND ROBERT McGREGOR, OF MONTCLAIR, NEW JERSEY.

STEAM SUPERHEATER.

Application filed October 20, 1919. Serial No. 332,107.

To all whom it may concern:

- Be it known that we, JAMES S. MILNE, residing at Brooklyn, in the county of Kings, State of New York, and ROBERT McGREGOR, residing in the town of Montclair, county of Essex, State of New Jersey, citizens of the United States, have invented a new and useful Steam Superheater, of which the following is a specification.
- 10 Our invention consists of a novel construction of steam superheater which can be adapted to existing boilers of every type without necessitating any change or dismantling of the latter, or employment of special fire tubes, provision being made for readily and expeditiously assembling the superheating devices with respect to any desired group of fire tubes in an existing boiler.
- 20 To the above ends, our invention consists of a novel construction of inlet and outlet manifold, adapted to be connected to a series of sectional headers and their adjuncts, which can be cheaply constructed, readily installed in position, with respect to any standard fire tube boiler, and which are conveniently accessible at all times for the purposes of inspection, replacement and repairs.
- 30 It further consists of a novel construction of a superheated steam header or main, an internal preferably cylindrical saturated steam main, an outer superheating tube open at one end and closed at the opposite end, collocated in a novel manner with a saturated steam circulating tube arranged concentrically within said superheating tube and properly positioned or centered with respect thereto, means being also provided for properly positioning said outer or superheating tubes with respect to the surrounding fire tube, whereby the relatively coolest steam is conveyed to the hottest part of the superheating tube, thereby reducing the temperature of said tube at this point.
- 40 It further consists of a novel construction of a saturated steam main wherein the cross-sectional area of said main decreases from its inlet end to its terminus.
- 50 It further consists of a novel construction and collocation of one or more valvular manually-operated devices, whereby a predetermined amount of saturated steam can

be admitted when desired, or according to requirements, to the supreheated steam preferably in the outlet manifold, for the purpose of reducing the temperature of said supreheated steam, when desired or expedient.

It further consists of a novel construction and arrangement of water circulating pipes so collocated with respect to the boiler proper and the superheater and its adjuncts or manifolds that said superheater, when desired can be temporarily flooded with water from the boilers, which will circulate through the superheater during the time of raising steam, provision being further made for readily and expeditiously draining the superheater or its manifolds according to requirements.

It further consists of a novel manner of collocating and assembling the superheater elements, whereby the inner and outer circulating and superheating tubes can be readily assembled or disconnected from the header sections, according to requirements or for the purposes of inspection, replacement or repair.

It further consists of a novel manner of collocating each superheater element with respect to its inclosing standard fire tube so that the operation of cleaning or the blowing out of the fire tube is not interfered with in any manner.

It further consists of a novel construction of corrugated outer or superheating tube, whereby the effective heating surface or area is increased.

To the above ends, our invention consists of a novel construction of steam superheater, wherein all the tubes are straight and return bends are dispensed with, thereby reducing friction and permitting any degree of superheat to be obtained by adding additional rows of tubes, and wherein a minimum number of joints are employed, thereby reducing the liability of leakage.

For the purpose of illustrating our invention, we have shown in the accompanying drawings certain forms thereof which are at present preferred by us, since the same will give in practice satisfactory and reliable results, although it is to be understood that the various instrumentalities of which our invention consists can be variously arranged and organized and that our invention is not

limited to the precise arrangement and organization of these instrumentalities as herein shown and described.

Figure 1 represents a front elevation of a Scotch marine boiler, showing our novel construction of superheater applied thereto, the boiler casing being removed.

Figure 2 represents on an enlarged scale a vertical section of the upper portion of Figure 1 on line 2—2 of said figure.

Figure 3 represents on an enlarged scale a transverse section of a header, saturated steam main, a superheater tube and a circulating tube, showing also the relative position of these parts to a standard fire tube.

Figure 4 represents a section on line 4—4 of Figure 3.

Figure 5 represents a section on line 5—5 of Figure 3.

Figure 6 represents on an enlarged scale, a section of the right-hand header, its saturated steam main, the outlet manifold, and the controlling valve for admitting saturated steam to the superheater, when desired.

Figure 7 represents on an enlarged scale, in detached position, a longitudinal section of one of the saturated steam mains seen in Figure 1, the section being taken on line 7—7 Figure 2.

Figure 8 represents on an enlarged scale, a side elevation of our novel corrugated superheater tube, the saturated steam main, header and coupling flange being shown in section.

Figure 9 represents a longitudinal sectional view of the parts seen in Figure 8, but showing the circulating tube and outer corrugated superheater tube in section.

Figure 10 represents a section on line 10—10 Figure 8.

Similar numerals of reference indicate corresponding parts.

Referring to the drawings:—

1 designates our novel construction of superheater, which is applicable to any type of boiler having standard fire tubes, as a land, marine, stationary or portable boiler, and in the present instance, we have shown a conventional type of Scotch marine boiler, having the main steam outlet 2, controlled by the main stop valve 3, from which leads the main steam pipe 4 to the superheater inlet manifold 5, which may have any number of saturated steam outlets, three being shown in the present instance.

Each of said outlets discharge the saturated steam into the saturated steam main 6, which is preferably constructed as seen in Figure 7, from which lead the circulating tubes 7, which are concentric with or positioned within the outer superheating tubes 8, each circulating tube having its end 9 terminating a short distance from the closed end 10 of its superheating tube 8, whereby a chamber is formed, so that the relatively

cool saturated steam is conveyed to the hottest part of the superheater tube, thereby reducing the temperature at this point.

The inner or circulating tube 7 is always maintained concentric with respect to the outer or superheating tube 8, by means of the radial centering lugs 11, and said outer tube 8 is maintained concentric with respect to the fire tube 12 by the radial lugs 13, as will be best understood from Figures 3 and 4, said fire tubes being secured in their tube sheets 14 and 15, in any suitable or conventional manner, and said fire tubes being of any standard or conventional size, and requiring no change or alteration when our novel superheater is applied thereto.

The open or left-hand end of the superheater tube 8 seen in Figure 3, is expanded and beaded or otherwise secured at 16 to the flange 17, which is bolted or otherwise secured in any conventional manner to the superheated steam header or main 18, which is preferably tubular and made in sections, as 19, 20 and 21 (as seen in Figure 1) both for convenience in handling and assembling and also to accommodate a plurality of groups of fire tubes. The main 6 is also preferably tubular and is arranged concentrically within the header 18, so that an annular superheated steam chamber 48 is formed.

For convenience of installation and simplicity of construction, we preferably make the two outer header sections as 19 and 21 in duplicate, the length of the intermediate section, as 20, varying according to requirements.

The three right-hand header sections as 21 are connected to the outlet manifold 22, seen at the right of Figure 1, which has the main outlet 23, from which the superheated steam is conveyed to the desired point. The inlet manifold 5 is provided with a drain pipe 24, having a valve 25 therein, and the outlet manifold 22 is provided with a similar drain pipe 26 having a valve 27 therein, said drains permitting the draining of each of said manifolds according to requirements.

27' designates a water circulating pipe, having its lower end connected to the bottom of the boiler as at 28, and provided with the valve 29, the upper end of said pipe being connected to the lower portion of the inlet manifold, as at 30, and being provided with the valve 31, as seen at the left of Figure 1.

The function of the pipe 27 is to provide for a circulation of water between the bottom of the boiler and the inlet manifold 5, and while it is not necessary, yet if desired, this circulation may be accelerated by the employment of a pump or other mechanical device 32, having the suction pipe 33, and the discharge pipe 34 connected to the pipe 27', as indicated at the left of Figure 1. As the pump 32 or its equivalent may be dis-

pensed with if desired, we have shown its suction and discharge in dotted lines.

35 designates a water circulating pipe leading from the outlet manifold 22 to the upper portion of the boiler and provided with the valves 36 and 37.

38 designates a small by-pass valve fitted to the end of one of the saturated steam mains 6, preferably the central main 6 as seen in Figure 1, and provided with the elongated valve stem 39 and suitable controlling mechanism 40 and a yoke fastened to the outside of the outlet manifold 22, see Figures 1 and 6, the function of said by-pass valve being to permit the passage of saturated steam directly into said outlet manifold without passing through the superheating tubes 8, whereby in the event of the temperature of the superheated steam being excessive, it can be instantly controlled or tempered by mixing saturated steam with said superheated steam in said outlet manifold upon the proper manipulation of said valve 38.

25 It will be understood from Figures 1 and 6, that the upper and lower saturated steam mains 6 are preferably constructed as seen in Figure 7, having their termini or right-hand ends closed, while the central main has its right-hand end open and provided with a valve seat 41, which is controlled by the valve 38, as seen in Figure 6, the valve stem 39 being supported and guided in the spider 42.

35 It will be obvious that either one of the plurality of mains 6 may have its end open and be provided with the valve 38, but we preferably locate this valve in the central main 6. Each of said mains 6 is preferably constructed as tapering from its inlet or left-hand end to its right-hand end, as will be understood from Figures 1 and 7, wherein we have shown said main 6 as composed of a plurality of sections as 43, 44 and 45, whose area in cross-section decreases from left to right, the contiguous juxtaposed ends of said tubes composing said saturated steam main being suitably secured together at any desired stage in the manufacture or assembling

50 of the device.

As already explained, it will be understood that the upper and lower mains 6, seen in Figure 3, when three are employed, are constructed substantially as seen in Figure 7, having their right-hand ends closed, while the central main 6 is preferably constructed as seen in Figure 6, and has its right-hand end open and provided with a valve seat as 41, for the purpose explained.

60 46 designates a safety valve applied to the upper portion of the outlet manifold 22, for the purpose of preventing excessive pressure in the superheater.

In the construction seen in Figures 8, 9 and 10, we have shown the employment of a

header 18, saturated steam main 6, and inner circulating tube 7 and flange 17 of the same character as already described, but employ a different form of superheater tube 47 having its outer surface corrugated, as will be best understood from Figure 10, whereby we are enabled to gain 40 per cent more heating surface over a plain tube.

It will be understood that in the constructions seen in Figures 2 to 5, we desire to be understood as disclosing the superheater tube 8 as corrugated, as best seen in Figure 10 at 47, but for the sake of clearness of illustration, we have shown the corrugated superheater tube particularly on an enlarged scale in Figures 8 to 10. The corrugated tube 47 is provided with the centering lugs 13 and is secured to the flange 17 in the same manner, as already described.

The operation is as follows:

Saturated steam generated by the boiler passes through the connection 2, valve 3 and main steam pipe 4 into inlet manifold 5, and then enters the saturated steam header 6 and flows through circulating tubes 7 into the superheating tubes 8. The flow is reversed in superheating tubes 8 and the steam passes between the outside of said circulating tube and the inside of said superheating tube back into an annular chamber 48 between the saturated steam header 6 and the main header 18. The above operation which has been described with respect to one pair of tubes takes place in the plurality of tubes seen extending across the entire front of boiler in Figure 1.

From the foregoing, it will be seen that from the time the steam leaves the circulating tube 7 and enters the superheating tube 8, it absorbs a considerable quantity of heat while passing between these two tubes, said tubes 8 being centrally located in the fire tubes 12 of the boiler and preferably running to within about six inches of the combustion chamber end of said fire tubes, the gases of combustion travelling between the outer periphery of tubes 8 and the inner periphery of tubes 12 on their way to the stack. These gases or products of combustion are obviously hottest at the point 10, where the relatively cool saturated steam first comes in contact with the superheating surfaces of the superheater tube 8. The superheated steam passes down the chamber 48 between the header 18 and saturated steam main 6 into the outlet manifold 22, from whence it is conveyed to any desired point. The small by-pass valve 38, shown in Figure 6, which is preferably located at the end of the central saturated steam main 6, can be conveniently manipulated from the exterior of the outlet manifold to moderate the temperature of superheat to any desired degree.

In other words, should the degree of su-

perheat be higher than desired, the valve 38 can be opened slightly, thereby permitting the saturated steam to flow directly into the outlet manifold 22, mixing therein with the superheated steam and reducing the temperature thereof to any degree desired.

The area of the outlet orifice 23 is considerably smaller than the total cross-section areas of the various spaces within 10 which the steam is forced to pass while being superheated, thereby reducing the velocity of the same and increasing the time which it takes for the steam to pass through the superheater, this construction giving the 15 steam ample time to absorb considerably more heat units than if its velocity had not been reduced.

The valve 46 is preferably a small spring-loaded safety valve which is fitted at some 20 convenient point on the outlet manifold 22, preferably at the upper portion thereof, to relieve excessive pressures within the superheater, which might be caused by closing the throttle valve on the engine and at the 25 same time closing the main stop valve 3 on the boiler, in which event, the safety valve would function. By providing the manifolds 5 and 22 with drains leading to some 30 convenient point, these drains can be used by the operating engineer to carry away any accumulation of water which may take place in the superheater.

By opening the proper valves in the pipes 27' and 35, the entire superheater unit can 35 be flooded with water up to the boiler water level, which is desirable when it is desired to circulate water through the superheater unit, while steam is being raised in the boiler, the auxiliary pump 32 being connected to the intake line 27' and being 40 adapted to augment the circulation, if desired, it being apparent that the presence of water in the superheater when steam is being raised in the boilers, precludes the 45 possibility of burning the superheater tube end 10, Figure 3, and it being further apparent that this feature of circulating the water in the superheater permits the raising of steam in a shorter time than heretofore, which is especially apparent when a 50 pump, as 32, is used. As soon as steam forms in the boiler, valves as 36 and 31 are closed by the operator and the drain valves 55 25 and 27 are opened, thereby permitting the superheater to be emptied, whereupon it can perform its function as a superheater.

Our entire apparatus is adaptable to boilers already in commission without any material change in their construction, since we do not have to alter or increase the size of the fire tubes, and do not occupy sufficient space in the uptakes to affect the flow or exit of the gases of combustion. The installation starting at the main stop valve 3 consists merely of a pipe line leading to

the inlet manifold 5, to which the transverse headers are bolted, the opposite ends of the right-hand transverse headers being connected to the outlet manifold 22 by any conventional flange bolting, while the saturated steam main 6 is secured within the main header 18 and reduces in size as it passes across the front of the boiler, the opposite end of each main 6 being blanked off in any suitable manner, excepting where 70 fitted with the valve 38, see Fig. 6.

We desire to call special attention to the gradual reduction in sectional area as from left to right of the saturated steam pipe 6, which reduction increases the effective area 80 between the outside of the main 6 and the inside of the header 18, the area being smallest at the extreme left and gradually increasing in size until its maximum at the extreme right, where the greatest amount of steam 85 must pass in order to enter the outlet manifold 22.

As will be noted from Figure 2, the headers are staggered in such a manner as to permit accessibility to the flange connections 17, 90 which are readily removable at all times.

Our header can be expeditiously and conveniently installed, since after manifolds 5 and 22 are bolted in position, a superheating tube 8 made up in flange 17 is entered into 95 each fire tube 12, which we may desire to utilize. The circulating tube 7 is then entered into the superheating tube 8. The left-hand section of the top header is then bolted in position, and the first section of the saturated steam main 6 is secured in place. The central section of the top header is then bolted in place and the central section of the superheated steam main 18 is secured into the first section. The third section of the 100 saturated steam main 6 is then secured into the central section, and the right-hand section of the header 18 is then bolted in place. After this is completed, the circulating tubes 7 are entered and screwed into the saturated steam main 6, after which the superheating tube 8 is slipped out and made fast to the header 18. This concludes the top row of the top header and the assembling of the other headers follows in similar order. 110

It will be apparent that the broad principle of our invention can be employed in other devices, such as feed water heaters and the like.

It will now be apparent that we have devised a novel and useful steam superheater which embodies the features of advantage enumerated as desirable in the statement of the invention and the above description, and while we have, in the present instance, shown and described preferred embodiments thereof which will give in practice satisfactory and reliable results, it is to be understood that the same is susceptible of modification in various particulars without departing 120 125 130

from the spirit or scope of the invention or sacrificing any of its advantages.

Having thus described our invention, what we claim as new and desire to secure by Letters Patent, is:—

- 5 1. In a superheater, a header, a saturated steam main located within said header, and tapering from its open inlet end to its terminus, steam superheating devices common to said header and saturated steam main, and a valve for controlling the smaller end of said saturated steam main for admitting saturated steam to the exit portion of the superheater when desired.
- 10 2. In a superheater, a header, a saturated steam main located within said header and of decreasing cross sectional area from its inlet end to its terminus, outer superheating tubes having one of their ends closed and their opposite ends secured to said header, and inner open-ended circulating tubes having one of their ends secured to said main and their opposite ends discharging against the closed ends of said superheater tubes, in combination with a valve for controlling the smaller terminal end of said saturated steam main to the exit portion of said superheater.
- 15 3. In a steam superheater, an inlet manifold, an outlet manifold, headers common to said manifolds, a saturated steam main lo-
- 20 cated within said headers and decreasing in cross-sectional area from its inlet end to its terminus, superheater tubes having one of their ends closed and their other ends secured to said header, and open-ended circulating tubes contained within said superheater tubes and having one of their ends secured in said saturated steam main and their opposite ends discharging against the closed end of said superheater tubes, in combination with a valve for controlling the smaller terminal end of said saturated steam main to the exit portion of said superheater.
- 25 4. In a steam superheater, an inlet manifold, an outlet manifold, a series of headers common to said manifolds, saturated steam mains located in said headers and having their cross-sectional area gradually reduced from their inlet ends to their termini, all of said mains having closed ends except one, which is provided with a valve seat, steam superheating devices common to said headers and mains, and a valve cooperating with said valve seat for effecting the commingling of saturated steam with the superheated steam in said outlet manifold.
